Primary Examiner — Ryan Harvey(74) *Attorney, Agent, or Firm* — Husch Blackwell LLP; George S. Pavlik(57) **CLAIM**

The ornamental design for an electronic gaming machine, as shown and described, except as disclaimed herein.

DESCRIPTION

FIG. 1 is a perspective view of the electronic gaming machine.

FIG. 2 is a front elevational view thereof.

FIG. 3 is a side elevational view thereof, the opposite side being a mirror image thereof; and,

FIG. 4 is a top plan view thereof.

The bottom and rear views of the electronic gaming machine illustrated in FIGS. 1-4 are hereby disclaimed and form no part of the claimed design.

The broken lines in the drawings illustrate portions of the electronic gaming machine that form no part of the claimed design.
